(57) **CLAIM**

The ornamental design for a cookware handle, as shown and described.

DESCRIPTION

FIG. 1 is a perspective view of a cookware handle shown attached to a pot according to an exemplary embodiment of the present invention;

FIG. 2 is a front elevation view of the cookware handle of FIG. 1;

FIG. 3 is a rear elevation view of the cookware handle of FIG. 1;

FIG. 4 is a left side elevation view of the cookware handle of FIG. 1;

FIG. 5 is a right side elevation view of the cookware handle of FIG. 1;

FIG. 6 is a top plan view of the cookware handle of FIG. 1;

FIG. 7 is a bottom plan view of the cookware handle of FIG. 1;

FIG. 8 is a perspective view of a cookware handle according to a modified form of the present invention;

FIG. 9 is a front elevation view of the cookware handle of FIG. 8;

FIG. 10 is a left side elevation view of the cookware handle of FIG. 8;

FIG. 11 is right side elevation view of the cookware handle of FIG. 8;

FIG. 12 is a top plan view of the cookware handle of FIG. 8; and,

FIG. 13 is a bottom plan view of the cookware handle of FIG. 8, with the rear view being the same as FIG. 3.

The broken lines are for illustrative purposes only and form no part of the claimed design.
